US00D795860S

(12) **United States Design Patent** (10) Patent No.: **US D795,860 S**
(45) Date of Patent: **** Aug. 29, 2017**

(54) **HOUSING FOR A COMPUTING DEVICE**

(71) Applicant: **Tactus Technology, Inc.**, Fremont, CA (US)

(72) Inventors: **Roman Rak**, Fremont, CA (US); **Mario Garcia**, Fremont, CA (US); **Curtis Ray**, Fremont, CA (US); **Forrest Grinstead**, Fremont, CA (US); **Katja Piililä**, Fremont, CA (US); **Kenny Woo**, Fremont, CA (US); **Michael Stanley Roberts**, Fremont, CA (US); **Hanna marie Bosmark**, Fremont, CA (US); **Gregorie Vandebussche**, Fremont, CA (US); **Christopher Kuh**, Fremont, CA (US)

(73) Assignee: **Tactus Technology, Inc.**, Hayward, CA (US)

(**) Term: **14 Years**

(21) Appl. No.: **29/510,629**

(22) Filed: **Dec. 1, 2014**

(51) LOC (10) Cl. **14-02**

(52) U.S. Cl.

USPC **D14/341**

CLAIM

We claim the ornamental design for a housing for a computing device, as shown and described.

DESCRIPTION

FIG. 1 is a back view of the housing for a computing device showing the new design;

FIG. 2 is the back-left perspective view;

FIG. 3 is the back-right perspective view thereof;

FIG. 4 is the front view thereof;

FIG. 5 is the top-right perspective view thereof;

FIG. 6 is the bottom-left perspective view thereof; and

FIG. 7 is the top view thereof;

FIG. 8 is the bottom view thereof;

FIG. 9 is the left-side view thereof;

FIG. 10 is the right-side view thereof;

FIG. 11 is another back-right perspective view in an alternative position; and,

FIG. 12 is another back-right perspective view in an alternative position.

The broken lines in the figures show portions of the housing for a computing device, which form no part of the claimed design.

1 Claim, 5 Drawing Sheets
